UNITED STATES PATENT OFFICE

JOHN BYFIELD, OF STRATFORD, ONTARIO, CANADA.

FEED MECHANISM FOR CIRCULAR-KNITTING MACHINES.

SPECIFICATION forming part of Letters Patent No. 231,476, dated August 24, 1880.

Application filed December 6, 1879.

To all whom it may concern:

Be it known that I, JOHN BYFIELD, of the town of Stratford, in the county of Perth and Province of Ontario, Dominion of Canada, manufacturer, have invented certain new and useful Improvements in Feed Mechanism for Circular-Knitting Machines; and I do hereby declare that the following is a full, clear, and exact description of the construction and operation of the same, reference being had to the annexed drawings, making a part of this specification, and to the letters and figures of reference marked thereon.

Figure 1 of the drawings is a representation of an elevation of my improved knitting-machine. Fig. 2 is a plan view of the same, and Figs. 3, 4, and 5 are detail views.

My invention relates to knitting-machines; and it consists in the improvements in the construction of the same hereinafter fully described, and particularly pointed out in the claims.

A indicates the cylinder of a circular-knitting machine, of the usual or any suitable construction, having needles a a, to which the yarns or threads of different colors are fed through guides or carriers B B'.

C designates a cam-cylinder, which surrounds the needle-cylinder, and carries a standard, D, through which the carriers B B' are arranged to slide.

The needle-cylinder is stationary upon a bed or table, E, while the cam-cylinder C rotates during the operation of knitting, thus carrying round the standard and yarn-carriers.

E' designates a rotary bobbin-table, which carries the bobbins G G, and H designates a rotary yarn-guiding roller-shaft, which is mounted in suitable bearings upon a standard, I, arranged above and intermediate of the knitting mechanism and the rotary bobbin-table.

The yarns or threads pass from the bobbins to the carriers through holes formed in collars upon the shaft H, and in order to prevent the threads from twisting together during the rotation of the carriers I provide means for rotating the bobbin-table and the yarn-guiding shaft in unison with the carriers, as follows:

Below the table E, I arrange a shaft, K, provided with a beveled-gear wheel, L, at each

one of its ends, one of the said wheels being arranged to engage with a line of gear-teeth upon the under side of the rotary table, and the remaining wheel to engage with a like line 55 of teeth at the base of the rotary cam-cylinder which carries the supporting-standard of the carriers.

Motion is likewise transmitted from the shaft K below the table to the shaft H upon 60 the standard I by means of a crossed belt, M, the entire mechanism being actuated by a gear-wheel arranged upon a crank-shaft so as to intermesh with the aforesaid line of teeth upon the rotary cam-cylinder C.

N designates a pattern-chain, which, like others of this class, is composed of links, some of which, according to any arbitrary arrangement, are cam-links N'. This pattern-chain is hung upon a sprocket-wheel, O, and its cam-links are arranged relatively to hinged rods Q, so that at stated periods during the operation of the machine rods Q will be acted upon by the cam-links for the purpose of raising cams R R' R² into the plane of contact with the 70 sliding carriers, so as to move the same into position for changing the feed from one color of yarn to another.

The rods Q, which are hinged upon the main table at Q', pass over the pattern-chain 80 and connect with rods which support the cams in such manner that one of the rods Q serves to raise but one of the cams R, while the remaining rod is employed for the purpose of raising simultaneously the remaining cams 85 R' R².

The sprocket-wheel is advanced at each revolution of the cam-cylinder which carries the yarn guides or carriers by means of a pivoted spring finger-bar, S, which is actuated by a 90 cam-projection, D', upon the bobbin-table E'. This finger-bar acts upon the teeth of a ratchet-wheel, T, which is secured alongside of the sprocket-wheel, whereby motion is imparted to the latter for the purpose of advancing the 95 pattern-chain, and hence bringing its cam-links successively against the rods Q.

The sliding carrier B is somewhat longer than the sliding carrier B', and both are provided with rollers B², which strike against the 100 cams as they are carried round by the rotary cam-cylinder.

The serial arrangement of the cams is such that spaces are left between the central cam, R, and the two outer cams, R' R².

The pattern-chain being previously arranged 5 to produce any number of stripes by the more or less frequent introduction into said chain of cam-links, the machine is put in operation, and at each revolution of the bobbin-table the cam-projection thereon strikes against and vibrates 10 the finger-bar, which strikes against the ratchet-wheel and thereby advances the chain one link. So long as the plain links pass over the sprocket-wheel the rods Q will remain inactive and no change of feeding-threads will be 15 effected. When, however, a cam-link comes over the wheel and directly under one of the said rods, the cam or cams connected therewith will be raised so as to enter the plane of contact of the sliding carriers. 20 Supposing the two cams R' R² to be the ones raised, the roller of the longer sliding carrier B will strike against the cam R' and cause this carrier to be projected toward the center of the needle-cylinder, while the roller of the 25 shorter carrier B', striking against the outer edge and passing around such curved edge of the cam R², will cause said shorter carrier to be shifted in a reverse direction. As the carriers are now carried round over the 30 needle-cylinder in such positions, the further advancement of the pattern-chain by the means above described will relieve the cam-pressure from the rod which has upheld the two cams, and hence these will drop down, while another 35 cam-link, coming against the rod which raises the cam R, will cause the same to rise into the plane of contact of the sliding carriers. The shorter carrier will now strike against the inner edge of the cam R—that is to say, the edge 40 which is nearest to the needle-cylinder—thereby causing the said carrier to be projected toward the center of the needle-cylinder, and the roller upon the longer carrier, coming against

the outer edge of the same cam, will cause the longer carrier to be retracted in a reverse direction, thus effecting a change of feed. 45

If desired, more than two bobbins may be carried upon the rotary bobbin-table, in which case the number of carriers, cams, and rods will be increased in like proportion. 50

Having thus described my invention, what I claim, and desire to secure by Letters Patent, is—

1. In a circular-knitting machine provided with a stationary needle-cylinder, revolving yarn-carriers, and mechanism for operating the same, the combination of the cams R R' R², the hinged rods Q, and the pattern-chain N, provided with cam-links N', substantially as and for the purposes set forth. 55

2. In a circular-knitting machine provided with a stationary needle-cylinder, revolving yarn-carriers, revolving bobbin-table, and mechanism for operating the same, in combination with the cams R R' R², the hinged rods Q, the pattern-chain N, provided with cam-links N', the sprocket-wheel O, ratchet-wheel T, spring finger-bar S, and mechanism for operating it, all constructed and operating substantially as and for the purposes set forth. 60

3. The rotary bobbin-table E', yarn-guiding roller-shaft H, rotary cam-cylinder C, provided with the sliding yarn-carriers B B', in combination with the shaft K, having beveled-gear wheels L, the gear-teeth on the bobbin-table 75 and cam-cylinder, and the belt M, for transmitting motion from the shaft K to the roller-shaft H, all substantially as set forth. 70

In testimony that I claim the above I have hereunto subscribed my name in the presence 80 of two witnesses.

JOHN BYFIELD.
